DEVICE FOR CLEANING GRATE BARS OF SINTERING MACHINES

Ancel L. Sapp, Blackwell, Okla., assignor to The American Metal Company, Limited, New York, N. Y., a corporation of New York

Application March 6, 1948, Serial No. 13,367

10 Claims. (Cl. 266—21)

1

This invention relates to an apparatus for cleaning grate bars of sintering machines and particularly those having a rotatable belt of movable grates held in pallets.

Cleaning devices have been proposed for cleansing adhering sinter in which the grate bars supporting the sinter were struck with considerable force by a pivotally mounted striking member operating to move simultaneously a number of the bars across the pallet. Present-day practice employs preferably grate bars which are able to withstand oxygen and sulfur dioxide at temperatures of about 1000° C., which is the usual sintering temperature. These bars ordinarily employ alloy steels which are resistant to the high temperature gases mentioned, but these steels are frequently brittle and apt to break when struck repeatedly. Regardless of breakage, this type of device has proved unsatisfactory for removal of sinter, with the result that after the pallets are recharged with ore and brought to sintering position, the flow of air has been impeded by the unremoved sinter and the sintering process using uncleansed grates has accordingly been interfered with.

The principal object of the present invention, accordingly, is to overcome these disadvantages, at least in part, and to provide a device giving better cleaning of the bars and less breakage. Other objects will be in part obvious and in part pointed out hereinafter.

The invention accordingly comprises the novel device and combinations thereof, specific embodiments of which are described herein by way of example only and in accordance with the manner in which I now prefer to practice the invention.

In the accompanying drawings forming part of this specification, Figure 1 is a side elevation partly in section of my improved apparatus;

Fig. 2 is a cross-sectional elevation along the lines 2—2 of Fig. 1;

Fig. 3 is a side enlarged elevation showing the lugs mounted on a rotatable cylinder and arranged to contact and move the grate bars of the pallets, and

Fig. 4 is a plan view of the showing in Fig. 3 with the pallets and bars removed, on a smaller scale.

Referring now to the drawings, numeral 1 designates a support for the apparatus as a whole; 2 designates movable grate bars pivotally mounted on pallets 3, each of which is supported by pairs of wheels 4 mounted at either end thereof and running on tracks 5 mounted on the frame 50

5 1. The pallets are secured together in the usual manner in the form of a rotatable belt running over wheels 6 and 7 in the usual manner. Ore or other material to be sintered is fed from a hopper 8 onto the grates and, as the wheels are rotated by a mechanism not shown in a counter-clockwise direction, the belt assembly of pallets and grates passes toward the left in Fig. 1 and, when it reaches the burners 9, is ignited in the usual manner. The mass on the grates burns from the top, air being forced through the mass and out through air boxes 10 and 11 under the grates. The mass is sintered at the time that it reaches the wheel 6 and the sintered mass is discharged as each pallet passes around the last-mentioned wheel and the discharged material passes through a chute 12 to storage or further treatment.

20 2. The grate bars 2 as shown in Figs. 2 and 3 are mounted about a pivot rod 13 extending from one side to the other of the pallet 3. These bars are arranged to lie parallel to one another and parallel to the direction of motion of the pallets. The bars in the pallets tilt about the pivot point 13 and are vibrated by a continuous vibrating means described below.

25 3. The tilting of the grate bars and vibration thereof is arranged in order to thoroughly clean the bars. It has been found that the discharge of the sinter as the pallets move over the wheels 6 is frequently incomplete and that sinter still remains on and between the bars and may interfere with proper sintering of the successive charges of ore placed on such grates unless removed. I prefer to employ a successive continuous vibration of the grate bars 2 in order to effect a thorough cleaning thereof. I accordingly provide beneath the pallet-grate structures while same are in an inverted position, a rotatable cylinder 14 and lugs 15 mounted thereon. The lugs as here shown each has a lower surface conforming to the curve of the cylinder which may have, for example, a radius of 7½ inches. Each lug rests on and is attached to the cylinder and has an upper curved surface which is about 3½ inches long and extends at an angle of about 30° to the surface of the cylinder upward in a flat curve to a maximum height of about 1 inch above the lower surface of the lug and, from the maximum point, descends to the opposite end of the lug in a circular arc. The distance designated as X in Fig. 3 between the last-mentioned end of the lug and a point on the lower surface of the lug immediately above the maximum height of the upper curved surface of

the lug is about 1 inch. The breadth of the lug designated by Y in Fig. 4 is about $3\frac{1}{2}$ inches. The dimensions given are preferred for a cylinder having approximately a 15-inch diameter and a length of about $37\frac{1}{4}$ inches. These dimensions will, of course, vary with the size of the installation. The cylinder is mounted near the discharge end of the sintering apparatus being supported by a shaft 16 driven by a V-belt 17 passing over a grooved pulley 18, the belt being driven preferably by a motor 19. The cylinder 14 is arranged to rotate in the same direction as the travel of the inverted grate bars and the lugs contact the bars and displace the sinter. As shown more particularly in Figs. 2 and 4, the lugs have curved or cam-like surfaces and are arranged to move the grate bars 2 successively and according to a pattern of movement, preferably as shown in the figures mentioned. As there shown, the lugs are set to move the bars, for instance, at about the center of the pallet, and then successively bars away from the center towards the outermost bars at each longitudinal edge of the pallet. For this purpose the lugs (Fig. 2) are mounted with one pair at the opposite ends of the cylinder 14. Each succeeding pair of lugs advance towards the transverse central plane of the cylinder 14 in steps with the front edge of each successive lug being in line with the rear edge of the next lug and so on to the central plane mentioned. The same arrangement is provided on the rear of the cylinder of Fig. 2. In this way, the lugs contact a grate bar at a given position on the pallet and thus successively other bars at positions toward the rear of the pallet to loosen sinter thereon. The action of the moving lugs on the grate bars is to give a successive continuous vibration of the grate bars.

The cylinder 14 is mounted on an adjustable semi-elliptical spring suspension including the semi-elliptical spring 20 having a stirrup suspension at one end 21 and an adjustable suspension provided by an upright bar 22 provided with a series of holes 23, into which pins 24 fit at the end of the spring opposite the suspension 21. By raising or lowering the left end of the spring in Fig. 3, the cylinder may be moved towards and away from the inverted pallets and grates. The reason for this adjustment is that certain sinters may require a more vigorous bumping than others. By raising or lowering the cylinder and lugs, the grate bars may be moved up or down, respectively, to a greater or lesser extent.

The sinter loosened and removed from the pallets and grate bars will fall downwardly into a chute 25 for collection and further use.

I have found that the apparatus operates successfully in use substantially without damage to grate bars and especially those adapted to withstand oxygen from the air and SO_2 at high temperatures of the order of $1000^{\circ} C$. Furthermore, the action of the rotatable cylinder and lugs is effective in cleaning out any sinter remaining on the pallets and grate bars after discharge of the main body of the sinter occurs.

While the invention has been described with respect to a preferred apparatus which gives satisfactory results, it will be understood by those skilled in the art after understanding the invention that variations, changes and modifications may be made in such apparatus without departing from the spirit and scope of the invention and it is intended in the appended claims

to cover all such changes and modifications. For instance, but without limitation, I have found that effective results are obtained by a linear speed of the grates and pallets of about two feet per minute with a depth of charge of about five inches, the speed of rotation of the cylinder 14 being about 43 R. P. M. Obviously, these speeds and dimensions may be varied without departing from the spirit and scope of the invention.

10. What I claim is:

1. In an apparatus for cleaning grate bars of sintering machines, in combination, movable pallets holding movable grate bars, said bars being mounted substantially parallel to the motion of said pallets, and means to gradually lift and lower at least one of said grate bars on one of said pallets and then successively other bars on the same pallet.

2. In an apparatus for cleaning grate bars of sintering machines, in combination, movable pallets holding movable grate bars, said bars being mounted substantially parallel to the motion of said pallets, and means to gradually lift and lower said bars in succession in each pallet to loosen sinter.

3. In an apparatus for cleaning grate bars of sintering machines, in combination, a driven belt of movable pallets holding movable grate bars, the grate bars being mounted substantially parallel to the motion of said pallets, and means to gradually lift and lower said bars in succession in each pallet when such pallet and bars are in an inverted position in order to loosen sinter therefrom.

4. In an apparatus for cleaning grate bars of sintering machines, in combination, a driven belt of movable pallets holding movable grate bars, the grate bars being mounted substantially parallel to the motion of said pallets, and a rotatable series of lugs beneath the belt arranged upon rotation to contact said grate bars in succession across each pallet to loosen sinter.

5. In an apparatus for cleaning grate bars of sintering machines, in combination, a driven belt of movable pallets holding movable grate bars, the grate bars being mounted substantially parallel to the motion of said pallets, a rotatable cylinder having lugs spaced on the face of the cylinder arranged to contact and move one of said grate bars on one of said pallets and then successively other bars on the same pallet.

6. In an apparatus for cleaning grate bars of sintering machines, in combination, a driven belt of movable pallets holding movable grate bars, the grate bars being mounted substantially parallel to the motion of said pallets, and lugs set to gradually lift and lower the bars at about the center of the pallet and then successively bars away from the center towards the outermost bars at each longitudinal edge of the pallet.

7. In an apparatus for cleaning grate bars of sintering machines, in combination, a driven belt of movable pallets holding movable grate bars, the grate bars being mounted substantially parallel to the motion of said pallets, and a rotatable cylinder having lugs mounted thereon with asymmetrically curved contact surfaces arranged to rotate in the same direction as the travel of the grate bars to contact the bars successively on the same pallet and displace sinter.

8. In an apparatus for cleaning grate bars of sintering machines, in combination, a driven belt of movable pallets holding movable grate bars, the grate bars being mounted substantially parallel to the motion of said pallets, a rotatable cyl-

sinter and lugs mounted thereon arranged to rotate in the same direction as the travel of the grate bars to contact the bars and displace sinter, said rotatable cylinder being mounted on a spring to permit motion of the cylinder towards and away from said grate bars.

9. In an apparatus for cleaning grate bars of sintering machines, in combination, a driven belt of movable pallets holding movable grate bars, a rotatable cylinder and lugs mounted thereon arranged to rotate in the same direction as the travel of the grate bars to contact the bars and displace sinter, said rotatable cylinder being mounted on a spring to permit motion of the cylinder towards and away from said grate bars.

10. In an apparatus for cleaning grate bars of sintering machines, in combination, a driven belt of movable pallets holding movable grate bars, the grate bars being mounted substantially parallel to the motion of said pallets, a rotatable cylinder, lugs mounted thereon arranged to rotate

in the same direction as the travel of the grate bars to contact the bars and displace sinter and supporting means for said cylinder comprising a spring to regulate the motion of the cylinder towards and from said grate bars.
